MEANS FOR SECURING PRINTING PLATES
TO THEIR CYLINDERS UNDER TENSIONTheodore R. Ziebell, Milwaukee, Wis., assignor to
C. B. Cottrell & Sons Company, Westerly, R. I.,
a corporation of Delaware

Application November 2, 1951, Serial No. 254,564

6 Claims. (Cl. 101—378)

1

This invention relates to means for securing printing plates to their cylinders under tension.

In plate securing means used in high speed rotary presses where the plate hooks are propelled along the cylinder grooves to and from their plate engaging positions by worm gears carried by the hooks and engaging the cylinder racks, the cylinder racks frequently become worn and broken because of the necessarily limited engagement of only one or two of the teeth of the worm gears with the teeth of the cylinder racks.

This invention is directed to plate tensioning means for overcoming these rack failures by providing a plate tension hook comprising coacting stationary and movable members; the stationary member having a row of teeth for extended engagement with the teeth of a cylinder rack to prevent endwise movement of the stationary member; the movable member, which carries the printing plate engaging jaw, being slideable along the stationary member to exert tension on the printing plate for securing it to its cylinder.

This invention is also directed to a plate tension hook having novel features of construction whereby the manually operated adjusting screw, which connects the stationary and movable members of the plate tension hook, is rotatably mounted against endwise movement in the movable member and has a screw threaded engagement with the stationary member.

This invention is also directed to a plate tension hook in which gearing is provided for operatively connecting the adjusting screw with a removable key or other suitable instrument.

A practical embodiment of my invention is represented in the accompanying drawings, in which

Fig. 1 represents a detail plan view showing a portion of a printing plate secured to its cylinder.

Fig. 2 represents a similar view on a much larger scale.

Fig. 3 represents a detail longitudinal section taken in the plane of the line 3—3 of Fig. 2;

Fig. 4 represents a detail cross section taken in the plane of the line 4—4 of Fig. 2;

Fig. 5 represents a detail cross section taken in the plane of the line 5—5 of Fig. 2;

Fig. 6 represents a side view of a key suitable for use in operating the movable hook member

2

and for turning one of the locks which slidably hold the movable member in its cylinder.

Fig. 7 represents an edge view of the said key.

The grooved base on which the printing plates 5 are to be secured under tension is shown as a plate cylinder 11 having spaced undercut spiral grooves 12 provided along their bottoms with toothed racks 13.

The marginal edge of the printing plate 14 10 is shown as having a reverse bevel formed by inclining the top surface of the edge inwardly and downwardly, as shown at 15, to be engaged by the plate tensioning jaw of the plate tension hook to be immediately described.

15 The plate tension hook for securing the printing plate 14 on the cylinder 11 by tension is shown as comprising a stationary member 16 and a movable member 17 in which the stationary member is housed.

20 The stationary member 16 is shown as provided with a row of teeth 18 along its bottom for extended engagement with the teeth of the cylinder groove rack 13 to lock the stationary member against endwise movement along the cylinder groove 12 when the plate tension hook has been inserted into the said groove at the desired point along the same adjacent the marginal edge of the printing plate 14.

The plate tensioning jaw 19 is turnably mounted on a clamp screw 20 which has a threaded engagement with the movable member 17 of the plate tension hook about midway its ends. This jaw 19 has a reverse bevel formed by inclining the end surface of the jaw inwardly and upwardly as shown at 21 for frictional engagement with the inclined top surface 15 of the marginal edge of the printing plate to exert tension thereon.

25 The movable hook member 17 of the plate tension hook is provided with two manually turnable double winged locks 22, 23 mounted in the movable member near its ends upon opposite sides of the plate tensioning jaw 19, in position to be turned into the small grooves 24 extending along the opposite side walls of the cylinder groove 12. This movable hook member 17 has a longitudinal bottom groove 17* which houses the stationary member 16; the side walls of said groove slidably engaging the side walls of the stationary member.

The manually turnable double winged lock 22 is shown as having an angular axial bore 25 for receiving the angular shank 26 of a suitable key 27 for turning the said lock 22 into and out of sliding engagement with the side grooves 24.

The manually turnable double winged lock 23 is shown as having an angular axial bore 28 for receiving the said angular shank 26 of the key 27.

The usual spring pressed balls 29, 30 may be employed to frictionally engage the double winged locks 22, 23 to yieldingly hold them in their withdrawn and extended positions. It will be noted that the plate tensioning jaw 19 is located between the two double-winged locks 22, 23.

The manually operated means for sliding the movable hook member along the stationary hook member, which is housed therein, is constructed, arranged and operated as follows:

An adjusting screw 31 which is located in the bottom groove 17* of the movable member operatively connects the two hook members 16, 17, the head of the said screw being rotatably mounted against endwise movement in the movable member 17 and the threaded shank of the said screw being passed through and having a screw threaded engagement with the stationary member 16 of the said hook within said bottom groove 17*.

The adjusting screw 31 has integral therewith a bevel gear 32 which meshes with a bevel gear 33 whose shank is rotatably mounted in the enlarged portion of the axial bore 28 of the turnable lock 23. This bevel gear 33 is provided with a smaller axial bore 34 for receiving the smaller shank 35 of the key 27 which may be inserted through the angular bore 28 of the gear 33.

In operation, the plate tension hooks are inserted into the cylinder grooves 12 in proper positions to cause the rows of teeth 18 of the stationary hook member 16 to bring the plate tensioning jaws 19 into position to receive the marginal edges of the plate 14 between the inclined end surfaces 21 of the jaws and the peripheral surface of the cylinder 11, the double winged locks 22 and 23, which are located upon opposite sides of the tensioning jaw 19, being first turned into their side grooves 24 to slidably hold the plate tensioning hook within the groove. The clamp screw 20 may then be turned to frictionally engage the marginal edges of the plate 14. The shank 35 of the key 27 may then be inserted into the angular bore 34 of the gear 33 to turn it and its meshing gear 32 of the screw 31 to cause the screw, because of its threaded engagement with the stationary hook member 16, to slide the movable hook member 17 along the stationary hook member 16 to cause the jaw 19 to exert tension upon the printing plate 14 to secure it firmly on the cylinder 11.

It will be understood that while the plate holding means is herein shown and described in connection with a curved printing plate and a spirally grooved cylinder, the plate holding means may be employed in connection with plates and their bases of any character within the scope of this invention.

It is evident that various changes may be resorted to in the construction, form and arrangement of the several parts without departing from the spirit and scope of this invention and hence it is not intended to be limited to the particular embodiment shown and described herein.

What I claim is:

1. A cylinder having spaced grooves, a printing plate and a plate tension hook comprising a stationary member having means for locking it in a cylinder groove against endwise movement, a movable member having a longitudinal bottom groove housing the stationary member, means for slidably holding the movable member in its cylinder groove, a plate tensioning jaw carried by said movable member independently of the means for slidably holding the movable member, a screw located in said bottom groove and operatively connecting the two members and a manually operated gearing for rotating the screw to slide the movable member along the housed stationary member for securing the plate on the cylinder under tension.

2. A cylinder having spaced grooves, a printing plate and a plate tension hook comprising a stationary member having means for locking it in a cylinder groove against endwise movement, a movable member having a longitudinal bottom groove housing the stationary member, means for slidably holding the movable member in its cylinder groove, a plate tension jaw carried by said movable member independently of said movable member holding means, a screw located in said bottom groove and rotatably mounted against endwise movement in the movable member and threaded into the stationary member, a gear on said screw, and a manually operated meshing gear carried by the first named means for rotating the screw to slide the movable member along the housed stationary member for securing the plate on the cylinder under tension.

3. A cylinder having spaced grooves provided with toothed racks, a printing plate and a plate tension hook, said plate tension hook comprising a stationary member having a row of teeth for extended engagement with one of said racks to lock the stationary member against endwise movement, a movable member having a longitudinal bottom groove housing the stationary member, two spaced manually turnable locks for slidably holding the movable member in its groove, a plate tension jaw carried by said movable member between said locks, and a manually operated means for sliding the movable member along the housed stationary member to secure the plate on the cylinder under tension.

4. A cylinder having spaced spiral grooves provided with racks, a printing plate and a plate tension hook comprising a movable member having a longitudinal bottom groove, two manually operated locks for slidably holding the movable member in its cylinder groove, a stationary member housed in said bottom groove of the movable member and provided with a row of teeth for extended engagement with a cylinder groove rack to lock the stationary member against endwise movement, a plate tension jaw mounted on said movable member between said locks and having a reverse bevel engagement with a marginal edge of said plate, and manually operated means for sliding the movable member along the stationary member to secure the plate on the cylinder under tension.

5. A printing plate tension hook comprising a stationary member provided with means for locking it against endwise movement in a plate cylinder groove, a movable member having a longitudinal bottom groove housing the stationary member, a plate tensioning jaw carried by the movable member, means on both sides of the said jaw for slidably holding the movable member in

the cylinder groove, and means for sliding the movable member along the housed stationary member.

6. A printing plate tension hook comprising a stationary member provided with a row of teeth for extended engagement with a plate cylinder groove rack for locking the stationary member against endwise movement along the cylinder groove, a movable member having a longitudinal bottom groove housing the stationary member, a plate tensioning jaw carried by the movable member, means on both sides of the said jaw for slidably holding the movable member in its cylinder groove, and means for sliding the mov-

able member along the housed stationary member.

THEODORE R. ZIEBELL.
